UNITED STATES PATENT OFFICE.

EDWARD ELLSWORTH PINKERTON, OF CHICAGO, ILLINOIS.

FOLDING DISPLAY BOX.

Application filed January 20, 1919. Serial No. 272,108.

To all whom it may concern:

Be it known that I, EDWARD ELLSWORTH PINKERTON, a citizen of the United States, and a resident of the city of Chicago, county 5 of Cook, and State of Illinois, have invented certain new and useful Improvements in Folding Display Boxes, of which the following is a specification.

My invention relates to improvements in 10 folding display boxes, the particular embodiment thereof disclosed in this application being designed for use especially in connection with hair pins.

The object of my invention is the production 15 of a folding box of the character mentioned which will be of durable and economical construction, one which will permit of ready and expeditious insertion of articles therein, effective display thereof when inserted, and which will securely hold the articles during shipment of the box.

Other objects will appear hereinafter.

The invention consists in the combinations and arrangements of parts hereinafter 25 described and claimed.

The invention will be best understood by reference to the accompanying drawings forming a part of this specification, and in which,

Fig. 1, is a top plan view of the blank used in the construction of the box, said blank being shown in flat or unfolded condition.

Fig. 2, a perspective view of the box in operative condition,

Fig. 3, a vertical section through the box,

Fig. 4, a section taken on line 4-4 of Fig. 3, and

Fig. 5, a section taken on line 5-5 of Fig. 4.

The preferred form of construction, as illustrated in the drawings, comprises a bottom 6 surrounded by lateral wall-forming members 7, 8, 9 and 10. Provided at the respective ends of the members 7 and 8 are elongated flaps or extensions 11 adapted, when the box is folded for use, to assume positions at the inner sides of the members 9 and 10, extending parallel therewith, as clearly seen in Fig. 4. The lateral wall

members 9 and 10 are formed with extensions 12, which are adapted to be folded inwardly to embrace the extensions 11, ears or flaps 13 being formed upon the portions 12 which are adapted to extend inwardly 55 therefrom along the bottom 6, as clearly seen in Fig. 4.

Formed upon the rear wall member 7 is a lid 14 having a flap 15 adapted, when the lid is in closed position, to assume a position in front of the wall member 8, a reduced extension 16 on the portion 15 being adapted for insertion into an elongated slot 17 formed at the base of wall 8 to hold the lid in closed position. Said lid is also formed with lateral flaps 18 adapted, when the lid is 60 in closed position, to assume positions at the inner sides of the lateral walls of the box, as clearly seen in Fig. 4.

Connected with the front wall-forming member 8 is a holder 19 for the articles to be 70 displayed, said holder being connected with said wall 8 by a portion 20 which, when the box is in operative condition, is adapted to be folded inwardly against the inner side of said wall 8 so as to bring the adjacent edge 75 of holder 19 in a position resting upon the bottom of the box, as clearly seen in Figs. 3 and 5.

The holder 19 is formed intermediate its ends with a transversely extending ridge 21 80 in the opposite sides of which are formed spaced aligning openings 22 adapted to receive the articles A for display. The cutting of the openings 22 results in the formation of resilient lips or flaps 23 adapted, upon insertion of the articles A into said openings, to yieldingly engage therewith, as clearly seen in Figs. 2, 3 and 4, so as to frictionally hold the articles against displacement. The outer edge of the ridge affords an excellent 85 surface for advertising matter, and the front flaps or lips 23 afford surfaces for designating the various sizes of hairpins or other articles which may be inserted into the various openings. The yieldability of 90 said ears also permits of a large or small number of articles or articles of various thicknesses being inserted thereunder.

The rearward edge of the holder 19 is provided with an extension or flange 24, which 100 is adapted to depend therefrom into contact with the bottom of the box in order to support said edge of the holder in slightly elevated position, thus affording a more attractive display for the articles held thereby. With the arrangement disclosed, it will be seen that the holder is positioned in a plane below the upper edge of the box, so that the articles arranged therein will be imprisoned between the front and rear walls 105 of the box, preventing accidental displacement thereof. In filling the box, that is,

inserting the articles into the openings 22, the rearward edge of the holder is raised and the flange 24 rested against the adjacent edge of the lid 14, with the latter swung back to full open position, said flange, in this position, serving as a guide for the articles in the inserting operation, insertion thereof being thus greatly facilitated.

When the holder 19 is in operative position within the box, it will be seen that the same is positioned directly over the inwardly projecting portions 13 connected with the side walls of the box, said holder thus serving as a means of locking said portions 13 in this position and hence of securely holding the box in distended or operative condition.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. A device of the class described comprising a box portion; a display holder mounted in said box portion, said holder being inclined relatively to the bottom of said box; and inwardly projecting ears on said box engaging under said holder whereby said box is locked in operative condition, substantially as described.

2. An adjustable holder comprising a body having a ridge therein, there being aligning openings formed in the opposite sides of said ridge for the reception of the articles to be displayed; and means for pressing against said articles to hold the same in position in said openings, substantially as described.

3. An adjustable holder comprising a body having a ridge therein, there being aligning openings formed in the opposite sides of said ridge for the reception of the articles to be displayed; and lips on said body at said openings, adapted to frictionally engage said articles to hold the same in position in said openings, substantially as described.

4. An adjustable holder comprising a body having a ridge therein, there being aligning openings formed in the opposite sides of said ridge for the reception of the articles to be displayed; and yieldable lips formed integral with said body at said openings, adapted to frictionally engage

5. A device of the class described com-

said articles to hold the same in position in said openings, substantially as described. 65 comprising a box portion; a holder for displaying articles arranged in said box portion, said holder having openings therein for the reception of said articles; and means formed from said holder for pressing against 70 said articles to hold the same in position in said openings, substantially as described.

6. A device of the class described comprising a box portion; a holder in said box portion; a ridge in said holder having aligning openings in opposite sides thereof for the reception of articles to be held; and means on said holder at said openings adapted to press against said articles to hold the same in position, substantially as described. 80

7. A device of the class described comprising a box portion; a holder in said box portion and formed integral therewith; a ridge in said holder having aligning openings in opposite sides thereof for the reception of 85 articles to be held; and means on said holder at said openings adapted to press against said articles to hold the same in position, substantially as described.

8. A device of the class described comprising a box portion; a holder in said box portion and connected with one side thereof; a ridge in said holder having aligning openings in opposite sides thereof for the reception of articles to be held; and means on 95 said holder at said openings adapted to press against said articles to hold the same in position, substantially as described.

9. A device of the class described comprising a box portion; a holder in said box portion; a ridge in said holder having aligning openings in opposite sides thereof for the reception of articles to be held; means on said holder at said openings adapted to press against said articles to hold the same in 100 position; and inwardly projecting ears on said box engaging under said holder, substantially as described.

10. A device of the class described comprising a box portion; a holder in said box portion; a ridge in said holder having aligning openings in opposite sides thereof for the reception of articles to be held; means on said holder at said openings adapted to press against said articles to hold the same in 110 position; and inwardly projecting ears on opposite sides of said box engaging under adjacent portions of said holder, substantially 115 as described.

In testimony whereof I have signed my 120 name to this specification in the presence of two subscribing witnesses.

EDWARD ELLSWORTH PINKERTON,
